(Cl. D4—3)

To all whom it may concern:

Be it known that Harrison S. Baker and Cathryn W. Baker, citizens of the United States, residing at Chicago, in the county of Cook and State of Illinois, have invented a new, original, and ornamental Design for Soap Holder, of which the following is a specification, reference being had to the accompanying drawing, forming part thereof.

In such drawing:

Fig. 1 is a top plan view of a soap holder, showing our new design;

Fig. 2 is a side elevational view thereof; and

Fig. 3 is a side elevational view taken 90° from that shown in Fig. 2.

We claim:

The ornamental design for a soap holder, substantially as shown.

HARRISON S. BAKER.
CATHRYN W. BAKER.
